UNITED STATES PATENT OFFICE.

TUDOR VAN AMSTEL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,337,736.

Specification of Letters Patent. Patented Apr. 20, 1920.

Application filed February 3, 1919. Serial No. 274,758.

To all whom it may concern:

Be it known that I, TUDOR VAN AMSTEL, a subject of the King of Great Britain, naturalized Canadian, residing at New York, in the county of New York and State of New York, have invented certain new and useful Improvements in Telephone-Exchange Systems, of which the following is a full, clear, concise, and exact description.

10 This invention relates to machine switching telephone exchange systems and more particularly to systems comprising several offices of different character.

15 The present invention has for its object the provision of an improved signaling system in which indicating devices are controlled by a plurality of small step-by-step switches over a metallic circuit by impulses 20 of various characteristics transmitted over said circuit.

In its more specific embodiment, the present invention is employed in an automatic telephone system in which calling lines terminating in a semi-automatic exchange may be connected to called lines terminating at a manual exchange. In such a system an operator at the semi-automatic exchange, after connecting her answering cord to the 30 calling line, sets one or more automatic switches under the control of a sending device to extend the calling line to the operator's position at the manual exchange. Since there can be no verbal communication 35 between two such operators, it is then necessary in completing the call to indicate the number of the wanted subscriber to the operator at the manual exchange. In the present disclosure the wanted number is indicated by sets of lamps, a set of lamps 40 being provided for each digit or character of the wanted number. These lamps are selectively operated in response to the operation of a sending device which is variably controlled by the operator at the semi-automatic exchange.

One feature of the invention consists in the control of an indicating device by a plurality of small step-by-step switches.

50 This and other features of the invention will appear in the accompanying drawing and description, together with the appended claims.

The drawing with Figure 2 placed below Fig. 1, diagrammatically represents a portion of a telephone system employing the present invention. Fig. 1 shows a calling subscriber's substation and line, with brushes of a district selector at the semi-automatic operator's position, a calling plug and jack at the manual operator's position and a called subscriber's substation apparatus and line. Within the small dotted rectangle at the left-hand side of Fig. 1, there are shown the brushes of a cord finder switch which is operated to connect an idle sending device to a cord circuit which has been connected to the calling line. Within the large dotted rectangle at the right-hand side of Fig. 1 there are shown the operator's key set and the registers for controlling the transmission of impulses to the number indicating device. Within the dotted inclosure in the middle of Fig. 1 there is shown an impulse transmitting device which, under the control of the registers, transmits various combinations of impulses to actuate the number indicating device. In Fig. 2 there is shown a set of relays which is actuated by the impulse transmitting device and a plurality of small step-by-step switches which are controlled in turn by such relays. There are also shown five sets of indicating lamps, one set for the indication of the station, one set for the indication of the thousands, one set for the indication of the hundreds, one set for the indication of the tens and another set for the indication of the units digit of the wanted number. Fig. 3 is a table showing the code of impulses for making the numerical selections and Fig. 4 is a similar table showing the code of impulses for making the selection of the stations.

In this disclosure the showing of the apparatus and the circuits for selecting the manual operator's position has been abbreviated, but it may be of the character of the system disclosed in the patent to Lundell No. 1,168,319, of January 18, 1916, or it may be similar to the system shown in the copending application of Clark No. 178,468, July 3, 1917.

The trunk selecting switch referred to in the description may be of the type illustrated in the patent to Craft and Rey.

nolds No. 1,123,696 of January 5, 1915, although it will be readily understood that any automatic selector switch can be employed in this system without departing from the spirit of the invention.

In the description, references are made to sequence switches and registers, the structure of which may be similar to that shown in the patent to Reynolds and Baldwin No. 1,127,808 of February 9, 1915.

In general, the system comprises a set of operators' keys which control sequence switch registers, all of which are shown in the dotted rectangle at the right in Fig. 1.

15 A device for sending impulses, as determined by sequence switch registers, is shown in the upper left-hand dotted inclosure of Fig. 1, and an arrangement of relays and small step-by-step switches for receiving 20 these impulses is shown in Fig. 2.

In Fig. 2 there are shown three relays in series, 201, 202 and 203 which respond directly to the transmitted impulses. These relays 201, 202 and 203 in turn control a 25 plurality of small step-by-step switches, one of which is used as a master switch to control the sequence of operation of the others.

There is provided a set of indicating lamps for each one of the digits of the 30 called number, each set of lamps being controlled by two of the small step-by-step switches.

The impulses transmitted by the device controlled by sequence switch 114 in Fig. 1 35 are in the nature of a code, these impulses being in a discontinuous train of positive and negative impulses of light and heavy current. The impulses of light current are produced through a grounded battery current flowing through a resistance 142 to the combination of sequence switch contacts 133 and 139. The impulses of heavy current are produced by grounded battery current flowing through a path which does not contain 40 a resistor.

The code of impulses is shown diagrammatically in the lower part of Fig. 2 under the two headings "Numerical code" and "Stations code." Each code character is 45 divided into six stages, and various numbers of impulses comprise each such code character. Invariably, the last stage contains no impulse. Invariably, also, the last impulse of a code character is one of heavy current. It may be said therefore that each code character comprises six stages, in each of which there is transmitted either no impulse, a light impulse of negative current or a light impulse of positive current, and a 50 last impulse of either positive or negative heavy current.

In order to give a clear understanding of the invention, a table, presented below, has been prepared on the assumption that the

number to be indicated is, for example, 65 4567-W. In such systems as the present, it is customary to send impulses representing the station, then the impulses representing the thousands, hundreds, tens and units digits in turn. The first column of the 70 table is a tabulation of the digit or character sent. The second column of the table is a tabulation of the stages of which the entire train of impulses is composed. The third column is a tabulation of the corresponding 75 positions of the sequence switch 114. The fourth column is a tabulation of the impulses transmitted. The light impulse of negative current being represented by the mark "—," the light impulse of positive current being indicated by the character "+," and the heavy impulses of negative and positive current being indicated by the characters "H—" and "H+." These tabulations of impulses may be checked by the 80 two tables appearing in Fig. 2. The fifth column is a tabulation of the points at which relays 201, 202 and 203 are operated. The examination of this table and a comparison of other columns will disclose the fact that 85 relay 201 is actuated whenever an impulse of heavy current of either positive or negative character is transmitted, and that relay 202 is always actuated when an impulse of positive current is transmitted, and likewise 90 relay 203 is actuated when a negative impulse is transmitted. It will furthermore be seen that when an impulse of heavy current is transmitted that two of such relays 95 are simultaneously actuated. The sixth column of this table is a tabulation of the positions of the master switch. An examination of this column will disclose the fact 100 that the master switch remains in one position until all of the impulses representing a certain character have been transmitted and relay 201 has been actuated. It will furthermore disclose the fact that the master switch is stepped from one position to the 105 next upon the cessation of a heavy impulse. The seventh column of this table is a tabulation of the step-by-step switch magnets as 110 they are operated. It will be apparent that while the master switch is, for example, in position 1, that magnets 205 and 206 are in a circuit to be actuated and are so actuated whenever relays 203 and 202 are actuated. When the master switch moves to position 2, magnets 207 and 208 are in circuit to be 115 actuated, and they in turn are energized in response to the actuation of relays 203 and 202. It so happens, in the example taken, that while the master switch is in position 2, relay 202 is at no time energized and hence magnet 208 does not become energized. In 120 column 8 there is an indication of the position in which the positive lamp arm of the step-by-step switch is found in the last stage.

of each digit. In like manner, column 9 shows the position in which the negative lamp arm is found in the sixth stage of each digit. In the tenth and last column is an indication of the particular lamp which is caused to glow when the positive and negative lamp arms have been properly positioned.

Digit.	Stage.	Pos.	Impulses.	Relay oper.	Master switch pos.	Switch magnet operated.	Pos. + lamp arm.	Pos. - lamp arm.	Lamp.

It is believed that the invention will be more clearly understood from the following detailed description of the method of establishing a connection of a calling subscriber as shown at 101 to a called substation as shown at 4567—W. When the calling subscriber removes his receiver from his switch-hook, a signal (not shown) is lighted at the semi-automatic operator's position. This operator thereupon connects the cord circuit conductors 103 and 104 to the calling line manually or by any other suitable means. As soon as the semi-automatic operator has connected the cord circuit to the calling line, a cord finder whose brushes are indicated at 105 and 106 operates to connect an idle sending device to the cord circuit taken for use.

When the semi-automatic operator connects the cord circuit to the calling line, she ascertains the number of the wanted subscriber and proceeds to set this up on the keyboard of her sending device.

It has been assumed that the wanted number is 4567—W. The operator will then depress the corresponding stations, thousands, hundreds, tens and units keys in response to which the associated sequence switch registers will be moved and the stations register 109 will come to rest in posi-

tion 5, the thousands register 110 will stop in position 4, the hundreds register 111 in position 5, the tens register 112 in position 6 and the units register 113 in position 7.

It will be assumed that the automatic trunk selecting switch, whose brushes are indicated by the numerals 107 and 108, has been set to select the proper trunk for connecting the calling subscriber with the manual operator's position in the office in which the wanted line terminates. It will also be assumed that the sequence switch associated with this trunk selecting switch has been moved into position 11.

After the sending device has been set and when the trunk selecting switch has been operated to extend the calling line to the manual operator's position at the desired office, the sequence switch associated with the cord finder will be in position 7, where a circuit will be established to move the sequence switch 113 out of position 1. This circuit may be traced from grounded battery, magnet of the sequence switch 114, contact 115, contact 116 of the cord finder sequence switch to ground. When sequence switch 114 is in position 2, a circuit is closed from ground, winding of relay 117, sequence switch contact 118, cord finder brush 105, contact 119, trunk selector brush 108, lower

armature and back contact of relay 120, winding 121 of the repeating coil, winding of relay 123 to grounded battery. Relays 117 and 123 are operated by current flowing over this circuit. At the armature and front contact of relay 117, a circuit is closed to ground through contact 124, magnet of the sequence switch 114 to grounded battery, to move this sequence switch out of position 2 and into position 3. At the front contact and armature of relay 123, a circuit is closed from ground through the left-hand back contact and armature of relay 125, lamp 126 to grounded battery. Lamp 126, in lighting, indicates to the manual operator that a call is waiting attention, and also indicates the trunk over which the call has been extended. The manual operator thereupon presses key 127 to associate the number indicating device with the trunk over which the call has been extended.

Upon the depression of key 127 a circuit is closed from ground, winding of relay 120, contact of key 127, conductor 128, winding of relay 200 to grounded battery. Relay 200 attracts its armature. Relay 120 attracts its armatures, and its lower armature and back contact interrupts the energizing circuit of relay 117. When this relay de-energizes, it closes a circuit from ground, its armature and back contact, contact 129, magnet of sequence switch 114 to grounded battery, to move sequence switch 114 out of position 3 and through its various operating positions back to position 1, during which a complete set of code impulses is transmitted to the relays 201, 202 and 203.

It will be assumed that a positive impulse is transmitted in the full numbered positions of sequence switch 114, that is when the lead 130 is connected through the sequence switch contact 133, and that a negative impulse is transmitted in the fractionally numbered positions of sequence switch 114, that is when the lead 130 is connected through the sequence switch contact 139. Thus, in position 4, of sequence switch 114, no impulse is transmitted since there is no connection between grounded battery through the contacts of sequence switch 109 to the lead 130. In position 4½, however, a circuit will be established from grounded battery, the resistance 142, sequence switch contact 131, sequence switch contact 132 to the lead 130, thence through the sequence switch contact 139, brush 106, sequence switch contact 135, brush 107, upper armature and front contact of relay 120, conductor 102, relay 201, relay 202, relay 203, conductor 134, lower armature and front contact of relay 120, brush 108, sequence switch contact 119, brush 105, sequence switch contact 140 to ground, thus producing a light impulse of negative current. Such impulses

will cause the actuation of relay 203, whereby a circuit is established from ground, armature and contact of relay 203, master switch arm 226 and its first position contact, winding of magnet 205 to grounded battery. Magnet 205 steps the positive lamp arm 215 to its second position contact.

In position 5 of sequence switch 114, a circuit is established from grounded battery, the resistance 142, sequence switch contact 138, sequence switch contact 141 to conductor 130, thence through sequence switch contact 133, brush 105 and over the circuit described to brush 106, sequence switch contact 136 to ground, thus producing a light impulse of positive current. Such impulse operates the relay 202, whereby a circuit is established from ground, armature and contact of the relay 202, master switch arm 227 and its first position contact, the winding of magnet 206 to grounded battery. Magnet 206 steps the negative lamp arm 216 to its second position contact.

In position 5½ a circuit is established from grounded battery, resistance 142, sequence switch contact 143, sequence switch contact 144 to the conductor 130, thence through sequence switch contact 139, brush 106, over the circuit previously described to brush 105, sequence switch contact 140 to ground, thus producing a second impulse of light negative current, and causing the positive lamp arm 215 to be moved to its third position.

In position 6 of sequence switch 114, a circuit is established from grounded battery, sequence switch contact 145, sequence switch contact 146 to the conductor 130, thence through sequence switch contact 133, brush 105 over the circuit described to brush 106, sequence switch contact 136 to ground, thus producing an impulse of heavy positive current. Such heavy positive current energizes both relays 201 and 202. Relay 202 causes the energization of magnet 206 whereby the negative lamp arm 216 is stepped to its third position. The energization of relay 201 establishes a circuit from ground, the armature and front contact of relay 201, relay 228 to grounded battery, whereby relay 228 is energized and locked through its inner armature and front contact to the ground at the normal contact of relay 229. In position 6½ of sequence switch 114, no impulse is sent over this circuit, hence the relays 201 to 203 are de-energized. Upon the de-energization of relay 201, a circuit is established from ground, the armature and back contact of relay 201, the outer armature and contact of relay 228, the winding of relay 229 to grounded battery. Relay 229 becomes energized in this circuit and transfers the ground at its normal contact from the winding of relay 228 to the winding of the master switch magnet 204. Master

switch magnet 204 thereupon steps its arms 226, 227 and 230 to their second position contacts, which brings the magnets 207 and 208 under the control of relays 203 and 202 respectively.

In this manner the positive and negative lamp arms are each stepped to the proper position such as shown, for example, in the table hereinbefore provided. Upon the 10 last heavy impulse of negative current in position 171 of sequence switch 114, the master switch magnet 204 steps its arms 226, 227 and 230 to their sixth position, whereupon a circuit is established from 15 ground, the sixth position contact of arm 230, the normal left-hand contact of relay 225, left-hand winding of relay 225 to battery and ground. Relay 225 becomes energized and through its inner right-hand 20 armature locks up to the ground provided on the armature and contact of relay 200. As relay 225 attracts its armatures, a circuit is established from ground, the arm 230 in its sixth position, the alternate left-hand 25 contact of relay 225, the contact and armature of magnet 204, winding of magnet 204 to battery and ground. Magnet 204 is energized in this circuit and steps the arms 226, 227 and 230 to their first or normal position. Relay 225, however, remains energized as long as relay 200 remains energized. At the outer right-hand armature and contact of relay 225, ground is placed 30 on the conductor leading to the positive 35 lamp arms, whereby the circuit for the selected lamps is completed. For instance, stations lamp W is included in a circuit from ground, the outer right-hand armature and contact of relay 225, the positive 40 lamp arm 215 and its third position contact, the lamp W, the negative lamp arm 216 and its third position contact to battery and ground.

The operator upon comprehending the 45 signal displayed by the different lamps, releases the key 127, whereby the circuit including relays 120 and 200 is broken and these relays become deenergized. The deenergization of relay 200 causes in turn the 50 deenergization of relay 225, and in turn the opening of the circuit for the supply of current to the indicating lamps. Relay 200 also at its back contact closes a circuit to restore the switches controlled by magnets 55 205 to 214 inclusive to their first positions. The arms of magnets 214 being in position two, a circuit is established from ground, the armature and back contact of relay 200, the arm 231 and its second position contact, 60 the contact and armature of magnet 214, winding of magnet 214 to battery and ground. Magnet 214 becomes energized and, being included in a self-interrupting circuit, steps its arms to their first or nor-

mal position. Thereupon a circuit is established from ground, the armature and back contact of relay 200, the arm 231, the arm 232 and its third position contact, contact and armature of magnet 213 winding of magnet 213 to battery and ground, whereupon 70 magnet 213 being included in a self-interrupting circuit moves its brushes to their first or normal positions. Likewise each one of the magnets 212 to 205 inclusive move their arms to their normal positions 75 in turn until the whole indicating device is returned to its normal position.

As the operator releases the key 127 she places the plug 161 into the jack 162 of the wanted subscriber's line, whereupon relay 80 125 becomes actuated.

It will be understood that as the impulse transmitting device 114 completes its operation, the cord finder whose brushes are designated by the characters 105 and 106, as 85 well as the associated sequence switch, is restored to normal. At the same time the sequence switch, contacts of which are shown associated with the trunk selecting switch, is moved out of position 11 to open 90 the contacts 119 and 135 and to close the contacts 164 and 165. Relay 123 is now energized as a calling supervisory relay and hence the lamp 126 is not included in an 95 effective circuit.

The operator at the manual position now depresses the proper button of the key 163 to ring the station W on the selected line.

At the close of the conversation, when the calling subscriber hangs up his receiver 100 a signal (not shown) is operated at the semi-automatic operator's position, and the operator proceeds to release the trunk selecting switch or other selecting switches 105 employed in the connection. When these switches are released, the circuit of relay 123 is opened and the lamp 126 is lighted to inform the manual operator that the call has terminated. This operator then removes plug 161 from jack 162.

Attention is directed to the circuit arrangement of the signal lamps and the positive and negative lamp arms. It will be noticed that a maximum of four steps of these arms is employed to separately include each of the lamps in an effective circuit. This may be clearly shown by the following table. Column 1 is a tabulation of the lamps. Column 2 is a tabulation of the positions of the positive lamp arm. Column 3 is a tabulation of the positions of the negative lamp arm. Column 4 is a tabulation of the number of steps taken by the positive lamp arm. Column 5 is a tabulation of the number of steps taken by the negative lamp arm. Column 6 is a tabulation of the total number of steps taken by the two switches. Since the lamp arms nor-

5 mally rest in their first positions, the number of steps taken is always one less than the number of the position in which they come to rest.

Lamp.	Pos. of +arm.	Pos. of -arm.	Steps taken by +arm.	Steps taken by -arm.	Total steps taken.
10	0	2	1	0	1
	1	1	0	1	1
	2	3	2	0	2
	3	2	1	1	2
	4	1	0	2	2
	5	4	1	3	3
	6	3	2	2	3
	7	2	1	2	3
	8	3	2	2	4
	9	4	2	1	3
15					

Thus it will be seen that through a maximum of four steps any one of the lamps may be included in an effective circuit.

20 It is not necessary that this specific arrangement be used, as the spirit of the invention is of broader scope and admits of many variations.

It will be understood that this disclosure 25 is merely typical of applicant's invention, and that its use is not limited to number indicating arrangements in automatic telephone systems or even in telephone systems broadly.

30 What is claimed is:

1. In a signaling system, an indicating device comprising a plurality of signals and a plurality of selectively operable step-by-step switches, a selectively operable step-by-step switch for controlling the sequence of operation of said first switches, a signaling circuit over which said indicating device is controlled, and means for propagating and transmitting impulses of certain characteristics to control said first switches and for propagating and transmitting impulses of other characteristics to control said second switch.

2. In a signaling system, an indicating 45 device comprising a plurality of signals and a plurality of selectively operable step-by-step switches for controlling said signals, a selectively operable step-by-step switch for controlling the sequence of operation of said first switches, a signaling circuit over which said indicating device is controlled, means for propagating and transmitting impulses of certain characteristics to control said first switches, and for simultaneously propagating and transmitting impulses of other characteristics to control said second switch.

3. In a signaling system, an indicating 60 device comprising a plurality of signals and a plurality of selectively operable step-by-step switches for controlling said signals, a selectively operable step-by-step switch for controlling the sequence of operation of said first switch, a signaling circuit over which said indicating device is controlled, and

means for propagating and transmitting a discontinuous series of impulses of various characteristics to control said step-by-step switches.

4. In a signaling system, an indicating device comprising a plurality of signals, a plurality of selectively operable step-by-step switches for controlling said signals, a selectively operable step-by-step switch for controlling said first switches, a signaling circuit over which said indicating device is controlled, and means for propagating and simultaneously transmitting one series of impulses to control said first switches, and a second series of impulses for controlling said second switch.

5. In a signaling system, an indicating device comprising a plurality of indicating signals, a plurality of selectively operating step-by-step switches for controlling each of said signals, a selectively operable step-by-step switch for controlling said first switches, a signaling circuit over which said indicating device is controlled, and means for propagating and transmitting a discontinuous series of impulses of various characteristics for controlling said indicating device.

6. In a signaling system, an indicating device comprising a plurality of sets of indicating lamps, a plurality of selectively operable step-by-step switches individual to each said set of lamps, a selectively operable step-by-step switch common to said set of lamps, a signaling circuit over which said indicating device is controlled, and means for propagating and transmitting a series of impulses for controlling said indicating device.

7. In a signaling system, an indicating device comprising a plurality of sets of indicating lamps, two selectively operable step-by-step switches individual to each said set of lamps, a signaling circuit over which said indicating device is controlled, and means for propagating and transmitting a series of impulses for controlling said indicating device.

8. In a signaling system, an indicating device comprising a set of indicating lamps for each character to be indicated, a pair of selectively operable step-by-step switches individual to each said set of lamps for selectively including a single one of said lamps in an effective circuit, a signaling circuit over which said indicating device is controlled, and means for controlling said switches over said circuit.

9. In a signaling system, an indicating device comprising a set of indicating lamps for each character to be indicated, a pair of selectively operable step-by-step switches for selectively including any one of said lamps in an effective circuit, a signaling circuit over which said indicating device is

controlled, and means for controlling in sequence over said circuit each said pair of switches.

10. In a signaling system, a set of signals, 5 a pair of switches for selectively including said signals in an effective circuit, each said switch comprising a series of contacts less in number than the number of signals, and a wiper for coöperating with said contacts, 10 said signals being included in effective circuits when the wipers of said switches are coöperating with their contacts in various combinations.

11. In a signaling system, a set of signals, 15 a pair of switches for selectively including said signals in an effective circuit, each said switch comprising a series of contacts less in number than the number of signals, and a wiper for coöperating with said contacts, 20 said signals being included in effective cir-

cuits when the wipers of said switches are coöperating with their contacts substantially a described.

12. In a signaling system, a set of ten signals, two switches for selectively including 25 said signals in an effective circuit, each said switch comprising a series of effective stationary contacts including a normal contact less in number than the number of lamps, and a wiper for coöperating with said contacts, 30 means for moving said wipers over said contacts, said signals being so connected to said contacts that a maximum of four steps taken by said switches will separately include each of said signals in an effective 35 circuit.

In witness whereof, I hereunto subscribe my name this 30th day of January, A. D., 1919.

TUDOR VAN AMSTEL.
